UNITED STATES PATENT OFFICE.

GEORGE BRADLEY, OF PATERSON, NEW JERSEY, ASSIGNOR TO JACOB S. ROGERS, OF SAME PLACE.

CAN-BOTTOM FOR ROVING.

Specification of Letters Patent No. 26,320, dated November 29, 1859.

To all whom it may concern:

Be it known that I, GEORGE BRADLEY, of Paterson, in the county of Passaic and State of New Jersey, have invented a new and useful Improvement in Can-Bottoms, which I term the "Duplex or Compound Can-Bottom," and by means of which the "coiler" may be used on the railway drawing-head; and I do hereby declare that the construction and operation of the same is described in the following specification and illustrated in its accompanying drawings with sufficient clearness to enable those skilled in the art to make and use my invention.

Figure 1 is a perspective view of my invention with two cans mounted thereon and with a small portion of the adjoining mechanism, and Fig. 2 is a horizontal section taken in a plane just above the bottom of the cans.

Similar letters of reference denote like parts in all the drawings.

The well known device known as the "coiler" is the best means of packing and compressing the rovings within a can; but owing to the difficulty and delay experienced in removing a filled can and substituting an empty one when a coiler is employed it has been practicable to apply it to such machines and such only as deliver the roving slowly. The roving which is delivered during the interval between the removal of one can and the introduction of another is liable to be wasted if it exceeds a certain very moderate length. With the can bottoms heretofore employed a coiler could not be successfully used on the "railway drawing head" on account of the great speed with which the cards must deliver the material in order to work with proper economy, and the consequently rapid delivery of the roving into the cans; and the rovings from this machine have consequently been packed into the cans by other and less perfect means in order to allow the cans to be more conveniently and rapidly exchanged.

My invention renders it practicable to employ the coiler on the railway drawing head or on any other however great may be the speed with which the roving is delivered. Its nature consists in so mounting two or more ordinary can bottoms in a frame capable of a partial or complete rotation, that the filled can may be removed from under the coiler and an empty one substituted in

its place by means simply of a partial revolution of the frame.

To enable others skilled in the art to make and use my invention, I will proceed to describe its construction and operation by the aid of the drawings, and of the letters of reference marked thereon.

A is the ordinary coiler attached to a railway drawing head or to any other from which the delivery of roving is too rapid to allow of conveniently changing the cans in the ordinary manner.

B and B' are two cans of the ordinary character to receive the rovings.

C C' are two ordinary can bottoms of corresponding size geared at their peripheries to the wheel D which through the aid of a train of wheels E E' E'' mounted beneath conveys a constant rotatory motion from the shaft *a* of the drawing head to both C and C'.

H is a platform or frame in which the can bottoms C and C' are mounted. It is capable of rotation around the center of the wheel D. The handle *h* is employed as a convenient means by which H may be turned at pleasure by the hand of the attendant.

When the parts are in the positions represented the can B' is being filled with roving through the coiler A while the can B is in a position to be readily and leisurely exchanged, being lifted off its bottom C if full and its place supplied by any empty one, each of the bottoms C and C' being properly rotated on its respective axis by the revolution of D. When the can B' is filled the attendant having previously placed an empty one on C grasps the handle *h* and by a simple and rapid lateral movement partially rotates H carrying the filled can B' out from under A to the position shown by the red line in Fig. 2 and carrying B under A to be filled. B' is now taken off at leisure and an empty can substituted in its place after which, when B is filled, the handle *h* is again grasped and the platform or frame H is turned back to the position represented. By this means the cans may fit very closely under A without a possibility of any loss of time in changing the cans. The roving simply stretches across from one can to the other, to be broken at leisure when the filled can is removed, and as the movement of H can if required be performed in a very small fraction of a second, the roving cannot be

delivered so rapidly as to reach the floor while the movement of H is progressing.

On the periphery of C above the gearing is a suitable projection c. On a suitable stud I fixed in H is loosely mounted the cam wheel K of the striking apparatus. The ordinary bell, hammer, and spring, are mounted upon I in the ordinary manner but instead of K being operated by a train of gearing from a as usual it is provided with a series of suitable springs or wings k adapted to be struck by c and to receive motion therefrom at each revolution of the cans. By making K and c of a proper size and providing a proper number of wings k the bell is made to strike after such a number of revolutions of C as are desired, and thus the bell is made to indicate when the cans are filled with the same effect as heretofore.

My invention allows the cans to be filled more regularly than heretofore and therefore allows the rovings to be delivered there-

from in better condition. It also allows cans of a given size to contain more roving by which the number of the cans may be reduced and the changes may be made less frequently. It also simplifies and perfects the striking mechanism by dispensing with the worm wheels and gearing heretofore required to reduce the motion.

Having now fully described my invention what I claim as new therein and desire to secure by Letters Patent is—

So mounting two or more ordinary can bottoms C C' that the filled can may be removed from under the coiler and an empty one substituted in its place by means simply of a partial revolution of the frame H, substantially as above described.

GEORGE BRADLEY.
